UNITED STATES PATENT OFFICE

159,047

GLASS WASHER

Thomas H. Corbett, Chicago, Ill.

Application November 18, 1949, Serial No. 6,114

Term of patent 14 years

(Cl. D49—1)

To all whom it may concern:

Be it known that I, Thomas H. Corbett, a citizen of the United States, residing at Chicago, in the county of Cook and State of Illinois, have invented a new, original, and ornamental Design for a Glass Washer, of which the following is a specification, reference being made to the accompanying drawings, forming a part hereof.

In the drawings:

Fig. 1 is a front perspective view illustrating a glass washer embodying my new design, the view being taken from the right-hand forward side of the machine;

Fig. 2 is another front perspective view illustrating further details of the design, the sliding rinse-compartment cover being removed;

Fig. 3 is a perspective view taken from the forward left-hand side of the machine; and

Fig. 4 is a rear perspective view of the machine with the sliding cover of the rinsing compartment removed.

I claim:

The ornamental design for a glass washer, substantially as shown.

THOMAS H. CORBETT.
